Primary Examiner—Ian Simmons*Assistant Examiner*—Dana L Sipos(74) *Attorney, Agent, or Firm*—Robert A. McCann; Christopher S. Clancy; James H. Williams(57) **CLAIM**

We claim the ornamental design for a keyboard for a hand-held printer, as shown and described.

DESCRIPTION

The FIGURE is a top plan view of a keyboard for a hand-held printer showing our new design.

The details shown in broken lines are for illustrative purposes only and form no part of the claimed design.
